UNITED STATES PATENT OFFICE.

EDUARD G.-L. KINDLER, OF FRIEDENAU, NEAR BERLIN, GERMANY, ASSIGNOR TO BERGISCHE STAHL-INDUSTRIE, OF OBERKASSEL, NEAR DUSSELDORF, GERMANY.

Brake

Application filed January 4, 1926, Serial No. 79,191, and in Germany November 23, 1925.

This invention relates to friction-brakes for railroad cars or other vehicles travelling on rails and consists essentially therein that the brake-shoes are applied to a brake-disc 5 which is mounted in radial direction upon an axle of the vehicle, and that a layer of yielding material, such as Ferodo-fiber, wood or the like, is inserted between said brake-shoe and said brake-disc, said layer serving as the 10 element of the brake which is exposed to wear. The brake in the present case will act in axial direction upon said brake disc. The yielding layer is preferably mounted upon the brake-shoe by having a plate or disc of sheet-metal interposed, to which said yielding layer 15 is fastened by means of rivets or the like. The rivets, serving for fastening the yielding layer upon said plate or disc of sheet-metal, are preferably made of copper and 20 arranged counter-sunk, and with heads of conical conformation. The brake-disc, which is mounted in radial direction upon the axle, is preferably polished at its surface which co-operates with the yielding layer of 25 Ferodo-fiber or the like. A rough braking surface of the brake-disc has been found to cause an excessive wear of the layer which serves as the brake-shoe or brake-block proper. In case a brake-disc is used, which 30 is acted upon by the brake-shoe on both of its sides, this brake-disc is preferably constructed as a double disc, the means for fastening said double disc upon the axle being then preferably provided between the two 35 individual discs of which the double brake-disc is composed. If such a double brake-disc is used, preferably both outer surfaces of the disc are smoothly polished. It is further desirable that the lever mechanism of the 40 brake, which is used for transmitting the forces from the actuating handle for the brake to the braking organs, is positioned in proximity to the latter. For this purpose preferably two double levers are employed 45 which are arranged in such a manner that they will be positioned crosswise with respect to each other, the lever arms which act upon the brake-shoes being essentially shorter than the lever arms which are connected with the 50 operating mechanism of the brake. Thus the lever mechanism will consist of two double levers of the form of bell-cranks, each comprising a shorter arm connected with the brake-shoe and a longer arm connected with the 55 operating mechanism of the brake, whereby said longer arms are arranged in crosswise manner. The lever mechanism is preferably mounted upon a support, which is suspended from the frame of the car. The ends of the longer arms of the bell-cranks are connected 60 with each other by a string or chain which is carried over a roller, the latter being connected with the operating mechanism of the brake. The brake-shoes, which are operated by the shorter arms of the bell-cranks, are 65 preferably loosely mounted upon the latter and are pressed away from the brake-disc by means of springs, which are mounted within a casing and laid around a pressure pin for the brake-shoes. 70

The drawing represents an example of the brake constructed according to this invention.

Fig. 1 is a side-view of the new brake,
Figs. 2 and 3 a top-view and front view 75 respectively, taken on Fig. 1,
Fig. 4 a diagrammatic view representing the general arrangement of the brake and
Fig. 5 a section representing in approximately natural size the mode of fastening the 80 layer, which serves as the brake-member proper, on the brake-shoe,
Fig. 6 shows a section of a part of the brake on a large scale.

In the drawing the reference letter *a* designates two discs, which are connected with each other by the walls or webs *a*¹. In order to facilitate the mounting of said discs *a* upon the axle, the former are made of two halves, which are connected with each other by means 85 of the screw-bolts *b* in such a manner, that said screw-bolts will be positioned between the two discs *a*. The discs *a* are smoothly polished on their exterior surfaces. The several parts of the discs *a* are constructed and 90 connected with each other in such a manner that there will be no axial motion of the one disc relatively to the other. The layer *c* serving as the braking member proper is made of a material of great resistance to wear 95 and more yielding than metal, such as Ferodo-fiber, wood or the like, and is fixed upon the plate or disc *c*² of sheet-metal by means of counter-sunk rivets *c*¹, as shown in Fig. 5, while the plate or disc *c*² is fixed to the brake-shoe *c*⁴ by means of the screw-bolts *c*³. The 100 brake-shoe pin *c*⁵ is surrounded by a helical spring *c*⁶, as shown in Fig. 2. The threaded pin *c*⁷ serves for adjusting the effective length of the brake-shoe pin *c*⁵. The bell-cranks *d* 105

110

are rotatably mounted at the points *g* upon the support *f* in a manner that the longer arms of said bell-cranks will cross each other. The shorter arms of said bell-cranks will act upon the brake-shoe pins *c⁵* and therewith upon the brake-shoes. The chain *h* is connected with one of its ends to the end of the longer arm of one of the bell-cranks and is carried over the roller *i*, while the other end of said chain 5 is connected to the end of the longer arm of the other bell-crank. Thus, in case of a different wear of the brake layers *c*, the arrangement of the chain *h* will provide a compensation for the difference of the effective lengths 10 of the two arms of one or both of said bell-cranks. The double lever *k*, as shown in Fig. 4, serves as the operating handle for the brake, the forces for operating the brake being applied at the ends *m* of said double lever 15 *k* either by the hands of the driver or by means of an electrically actuated solenoid or the like. On the double lever *k* there are further provided rollers *o* at points, which are positioned near the point of rotation of said 20 double lever. The rollers *i* are connected with each other by a flexible string *n* or the like, which is carried over and between said rollers *o* in the manner indicated in Fig. 4 of the drawing. The string *n* will also be 25 able to provide a compensation for uneven wear of the layers *c*, the same as the chains *h*. By reason of the fact that the points of rotation of the rollers *o* are positioned relatively closely to the point of rotation of the double 30 lever *k*, the first force-increasing lever action of the operating mechanism of the brake will take place at the rollers *o* while a further force-increasing lever action will take place at the bell-crank *d* due to the different 35 lengths of the two arms thereof. The pivot (not shown) of the lever *k* is supported by the under frame of the vehicle. The spring *c⁶* is 40 fully enclosed in a casing *p*, so that said spring will be fully protected against soiling. 45 The support *f* which serves as a bearing for the brake-shoes *c⁴* and the bell-cranks *d* is mounted by means of the arms *q* in suspended condition on the bottom or underframe of the car, as may especially be seen from Fig. 3. 50 By this a relative motion between the brake-shoes *c⁴* which carry the layer *c*, and the discs *a* will be made possible in perpendicular direction. A bar *r* is connected to the under frame of the car and serves as an abutment 55 for the support, thus preventing the support and brake shoes from swinging away from the disc.

I claim:

1. In a friction brake for rail vehicles, a 60 brake operating device, a brake disc radially mounted on a rotatable axle of the vehicle, a brake shoe opposite each lateral surface of the said disc and arranged to move substantially in the direction of said axle, a bell- 65 crank lever for each shoe arranged to swing

in a plane perpendicular to the said surface, one arm of each lever acting on a brake shoe, the other arm being connected with the said brake operating device, the levers actuating the brake shoes only in their engaging direction. 70

2. In a friction brake for rail vehicles, a 75 brake operating device, a brake disc radially mounted on a rotatable axle of the vehicle, a brake shoe opposite each lateral surface of the said disc and arranged to move substantially in the direction of said axle, a bell-crank lever for each shoe arranged to swing in a plane perpendicular to the said surface, one arm of each lever acting on a brake shoe, 80 the other arm being connected with the said brake operating device, the levers actuating the brake shoes only in their engaging direction, the arms of the levers which are in connection with the said brake operating device 85 being longer than the other arms and crossing each other.

3. In a friction brake for rail vehicles, a 90 brake disc mounted radially on a rotatable axle of the vehicle, a brake shoe opposite each lateral surface of the said disc and arranged to move substantially in the direction of the said axle, two levers each adapted to act on a brake shoe, means for moving the said levers, the free ends of the said levers being 95 arranged to be engaged by said means, and a device for compensating uneven wear of both of said brake shoes and for effecting an equal distribution of the braking forces to the said levers. 100

4. In a friction brake for rail vehicles, a 105 brake disc mounted radially on a rotatable axle of the vehicle, a brake shoe opposite each lateral surface of the said disc and arranged to move substantially in the direction of the said axle, two levers each adapted to act on a brake shoe, means for moving the said levers, the free ends of the said levers being arranged to be engaged by said means, and a device for compensating uneven wear of both of said 110 brake shoes and for effecting an equal distribution of the braking forces to the said levers, said compensating device comprising a flexible member connecting the free ends of said levers and a roller engaged by said 115 lever moving means, the said member being carried over the said roller and rolling freely on the latter.

5. In a friction brake for rail vehicles, a 120 brake operating device, a brake disc radially mounted on a rotatable axle of the vehicle, a brake shoe opposite each lateral surface of the said disc and arranged to move substantially in the direction of said axle, a bell-crank lever for each shoe arranged to swing in a plane perpendicular to the said surface, one arm of each lever acting on a 125 brake shoe, the other arm being connected with the said brake operating device, the levers actuating the brake shoes only in their 130

engaging direction, means for guiding each brake shoe, and a member connecting the guiding means of the brake shoes.

6. In a friction brake as claimed in claim

5 1, means for guiding each said brake shoe, a member connecting the guiding means of the two brake shoes, and suspending means for suspending said member to the under-frame of the vehicle and permitting a swing-
10 ing movement of the member.

7. In a friction brake as claimed in claim 1, means for guiding each said brake shoe, and a member for connecting the guiding means of the said two brake shoes, the pivots
15 of the said levers being arranged on the said member.

8. In a friction brake for rail vehicles, a
brake operating device, a brake disc radially
20 mounted on a rotatable axle of the vehicle, a

brake shoe opposite each lateral surface of the
said disc and arranged to move substantially
25 in the direction of said axle, a bell-crank
lever for each shoe arranged to swing in a
plane perpendicular to the said surface, one

arm of each lever acting on a brake shoe, the
other arm being connected with the said
brake operating device, the levers actuating
30 the brake shoes only in their engaging direction,
means for guiding each brake shoe, and

35 a member for connecting the guiding means
of the two brake shoes, the pivots of said
levers being arranged on the said member
and near the guiding means of the respective
brake shoes.

40 9. A friction brake for rail vehicles, com-
prising a brake disc mounted rotatably but
not slidably on a rotatable axle of the vehicle,
two brake shoes each arranged to be moved
substantially in the direction of said axle
45 against one of the lateral surfaces of the said
disc, and means moved in the same direction
as the brake shoes and to take with it the
brake shoes only in one direction of move-
ment, a pin on each brake shoe adapted to
50 be engaged by the said means.

55 10. A friction brake for rail vehicles, com-
prising a brake disc mounted radially on a
rotatable axle of the vehicle, two brake shoes
each arranged to be moved substantially in
the direction of said axle against one of the
60 lateral surfaces of the said disc, and means
for each shoe moved in the same direction
as the brake shoes and to take with it the
brake shoes only in one direction of move-
ment, a spring for releasing each brake shoe
65 from the said brake disc and tensioned by
said means.

70 11. A friction brake for rail vehicles, com-
prising a brake disc mounted radially on a
rotatable axle of the vehicle, two brake shoes
each arranged to be moved substantially in
the direction of said axle against one of the
75 lateral surfaces of the said disc, and means
for each shoe moved in the same direction as
the brake shoes and to take with it the brake
shoes only in one direction of movement, a layer of yield-
ing material on the braking surface of each
80

shoes only in one direction of movement, a
spring for releasing each brake shoe from
the brake disc and tensioned by said means,
and a casing for guiding each brake shoe, the
said spring being enclosed in said casing.

70

12. A friction brake for rail vehicles, comprising a brake disc mounted radially on a rotatable axle of the vehicle, two brake shoes each arranged to be moved substantially in the direction of said axle against one of the lateral surfaces of the said disc, and means moved in the same direction as the brake shoes and to take with it the brake shoes only in one direction of movement, a pin on each
85
brake shoe engaged by said means, a coil spring on each pin for releasing the brake shoes from said brake disc and tensioned by said means, and two casings each for guiding a brake shoe, enclosing said spring and surrounding said pin.

85

13. A friction brake for rail vehicles, comprising a brake disc mounted radially on a rotatable axle of the vehicle, two brake shoes each arranged to be moved substantially in the direction of said axle against one of the lateral surfaces of the said disc, and means for each shoe moved in the same direction as the brake shoes and to take with it the brake shoes only in one direction of movement, and a layer of yielding material interposed be-
90
tween each brake shoe and said brake disc.

95

14. A friction brake for rail vehicles, comprising a brake disc mounted radially on a rotatable axle of the vehicle, two brake shoes each arranged to be moved substantially in the direction of said axle against one of the lateral surfaces of the said disc, and means for each shoe moved in the same direction as the brake shoes and to take with it the
100
brake shoes only in one direction of move-
ment, and a layer of yielding material mount-
ed on each brake shoe.

105

15. A friction brake for rail vehicles, comprising a brake disc mounted radially on a rotatable axle of the vehicle, two brake shoes each arranged to be moved substantially in the direction of said axle against one of the lateral surfaces of the said disc, and means for each shoe moved in the same direction as the brake shoes and to take with it the
110
brake shoes only in one direction of move-
ment, a layer of yielding material mounted on
each brake shoe, and the surface of said disc
co-operating with said brake shoes being pol-
ished before use.

115

16. A friction brake for rail vehicles, comprising a brake disc mounted radially on a rotatable axle of the vehicle, two brake shoes each arranged to be moved substantially in the direction of said axle against one of the lateral surfaces of the said disc, and means moved in the same direction as the brake
125
shoes and to take with it the brake shoes only in one direction of movement, a layer of yield-
ing material on the braking surface of each
130

brake shoe, the disc comprising two disc shaped bodies spaced apart and means within the space between the inner surface of the said bodies for bracing the latter against each other.

17. In a friction brake for rail vehicles, a brake operating device, a brake disc radially mounted on a rotatable axle of the vehicle, a brake shoe opposite each lateral surface of the said disc and arranged to move substantially in the direction of said axle, a bell-crank lever for each shoe arranged to swing in a plane perpendicular to the said surface, one arm of each lever acting on a brake shoe, the other arm being connected with the said brake operating device, the levers actuating the brake shoes only in their engaging direction, a layer of yielding material on the braking surface of each brake shoe, the disc being composed of two bodies each comprising two semi-circular plates spaced apart, means between the inner surfaces of the said plates for bracing the discs against each other and other means within the said space for fastening the said bodies together to form a compact member of disc wheel form.

18. A friction brake for rail vehicles, com-

prising two brake surfaces fastened radially and not slidably on a rotatable axle of the vehicle, two brake shoes, each opposite one of said brake surfaces and arranged to be moved in the direction of said axle against said surface, and means arranged to move in the same direction as the brake shoes to take with it each brake shoe only in one direction of movement.

19. A friction brake for railway vehicles, comprising a brake disc mounted radially on a rotatable axle of the vehicle, a brake shoe arranged opposite each lateral surface of said disc, each shoe arranged to be moved substantially in the direction of said axle against the disc, and means for each shoe moved in the same direction as the shoes to take its shoe with it only in one direction.

20. A friction brake according to claim 19, wherein said means comprises a bell crank lever arranged to swing in a plane perpendicular to the friction face of a shoe, and a brake operating device, one arm of said lever moving the shoe and the other arm connected with said device.

In testimony whereof I affix my signature.

EDUARD G. L. KINDLER.
